UNITED STATES PATENT OFFICE.

CHARLES W. RIBBLE, OF TOLEDO, OHIO.

LEVER LOCK.

1,408,225.

Specification of Letters Patent. Patented Feb. 28, 1922.

Application filed February 26, 1921. Serial No. 448,145.

To all whom it may concern:

Be it known that I, CHARLES W. RIBBLE, a citizen of the United States, and a resident of Toledo, county of Lucas, and State of Ohio, have made an invention appertaining to Lever Lock; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to means particularly for use in connection with the ball type of gear shift or control levers of automobiles to lock the same in neutral or inoperative position.

The object of my invention is the provision of a locking means of the character described, which is simple and efficient in its construction, and capable of being easily and quickly applied to a lever and of being operated to lock the same in neutral or inoperative position or to release the same.

The invention is fully described in the following specification, and while, in its broader aspect it is capable of embodiment in numerous forms, a preferred embodiment thereof is illustrated in the accompanying drawings, in which,—

Fig. 1 is a side elevation of a lock embodying the invention in operative locking engagement with a control lever and with parts broken away. Fig. 2 is a central vertical section thereof with parts in full and Fig. 3 is a cross section thereof.

Referring to the drawings, 1 designates a hollow standard or housing with its upper portion contracted and open at its top and having a cross shaft 2 mounted with its ends projecting beyond the sides of the housing. The control lever 3 projects down into the housing and is mounted on the shaft 2 for universal rocking movements thereon to adapt it to be shifted longitudinally or transversely thereof as is customary with levers of this type, and its lower end projects down through the housing to connect with the parts to be shifted. A hood or shell 4 of semi-spherical form fits down over the upper end of the housing 1 for universal shifting movements thereon and has an opening in its top which closely receives the lever 3. The hood 4 has its lower edge provided with

notches 5 at opposite sides thereof for loosely straddling the projecting ends of the pivot pin 2. The features above described are common to shift levers of the ball shift type except that the ends of the pin 2 do not customarily project beyond the sides of the housing 1.

In carrying out my invention I mount a cylindrical shell 6 around the upper contracted end of the housing 1, which shell has openings 7 in opposite sides thereof for receiving the projected ends of the pivot pin 2. The lower end of the shell is clamped to the housing in the present instance, by set screws 8. The shell 6 at its upper end has its wall inwardly curved in concentric relation to the hood 4 and is provided at one side with an opening 9. A cap 10 is fixedly mounted on the lever 3 over the hood 4 in spaced relation thereto and has its skirt portion curving outward and downward substantially in concentric relation to the hood 4 and upper end portion of the shell 6 and at the outer side of the latter, whereby the cap may have rocking movements with the lever relative to the shell 6. The lower edge of the cap 10 laps the upper end of the shell 6 and is provided at one side with an outwardly projecting cylindrical boss 11 which is hollow or axially bored to receive a lock barrel 12 for longitudinal or axial shifting movements therein.

The lock barrel 12 is provided at its inner end with a locking stud or projection 13 adapted to enter the hole 9 and for locking coaction with the shell 6 when the lock barrel is at the limit of its inward movement and the lever 3 is in neutral position. The barrel 12 carries a locking mechanism of the cylinder lock type, the bolt or locking member 14 of which is adapted to enter either one of a pair of sockets 15 and 16 in the wall of the boss 11 to respectively lock the barrel in either locked or released relation to the shell 6, as is apparent. A screw 17 projects through the wall of the boss 11 and into a longitudinally extending slot 18 in the side of the barrel 12 to coact with the ends of the slot to limit the shifting movements of the barrel. It is evident that even though the screw 17 were removed the barrel could not be withdrawn from the boss when the bolt 14 was engaged with either socket 15 or 16.

A pin 19 is inserted into a cross-hole 20 in the hub portion of the cap and through

a registering hole in the lever 3 to secure the cap in position on the lever. In order to prevent the pin 19 from being driven out of the hole 20 a hole 21 is drilled or 5 provided in the cap 10 in intersecting relation to an end of the hole 20 and terminating at one end in the interior of the boss 11, the cap being formed with a web 22 extending from the hub portion of the cap 10 to the boss 11 for such purpose. A lock pin 23 is inserted in the hole 21 at one end of the pin 19. It is thus evident that if the pin 19 has both ends terminating within the 15 hole 20 and one end in abutment with the pin 23 it cannot be driven from the hole 20, and it is also evident that if the pin 23 terminates at both ends within the hole 21 it can only be removed from the hole by first removing the lock barrel 12 from 20 the boss 11 and then inserting a tool through the interior of the boss and into the inner end of the hole 21 to drive or force the pin outwardly from the hole.

24 designates a coiled compression spring 25 which is interposed between the hood 4 and hub portion of the cap 10 with its ends-thrusts thereagainst so as to yieldingly retain the hood 4 seated on the upper end of the housing 1. In order to lock the pin 2 against 30 removal from the shell 6 and housing 1 when the lever is in locked neutral position the cap 10 is provided at opposite sides thereof with downward extensions 25 which lap respective ends of the pin 2.

35 It is evident that I have provided a simple and efficient lock which is capable of being easily and quickly applied to certain types of gear shift control levers now in use; that it is composed of few parts and 40 is capable of being easily operated to lock the lever in neutral position or to release the same, and at the same time is of such a nature as to make it exceedingly difficult to be broken or released except by the use 45 of a key suitable for the lock.

I wish it understood that my invention is not limited to any specific construction, arrangement or form of the parts, as it is capable of numerous modifications and 50 changes without departing from the spirit of the claims.

Having thus described my invention, what I claim as new and desire to secure by Letters Patent, is,—

55 1. In combination, a housing, a cross pin mounted in the upper part of the housing and having its ends projecting beyond the same, a shift lever mounted on the pin with-

in the housing for universal shifting movements, a shell embracing the upper end of 60 the housing and carried by the projected ends of the pin, said shell having an opening in its side wall, a member fixed to the lever and having a part overhanging the portion of the shell in which the opening 65 is disposed, and locking means carried by the member for movement into and out of locking engagement with the shell opening and adapted to be locked to the member in either locking or released relation to the 70 shell.

2. In combination, a housing, a cross pin mounted in the upper portion of the housing, a shift lever fulcrumed on the pin within the housing for universal shifting 75 movements and having its ends projecting beyond the housing sides, a shell enclosing the upper end of the housing and having a lock opening and openings for receiving the projected ends of the pin, a cap fixedly 80 carried by the lever and having its skirt extending down around the upper portion of the shell and having parts which lap the ends of the pin when the lever is in neutral position, said cap having an apertured boss 85 at one side thereof, a locking barrel mounted in the boss for shifting movements toward and away from the shell and having an inner end part for movement into and out of the lock opening of the shell, and means 90 carried by the barrel and operable to lock it to the cap in released or locking relation to the shell.

3. In combination, a shift lever, means receiving an end of the shift lever and in which it is fulcrumed, a member mounted on the shift lever and having a part extending down at a side of said means and provided with an opening, locking means removably mounted in the opening and 100 operable to engage the first means and lock the cap and lever against shifting movements relative thereto, said member and shaft having a registering cross hole there-through and the member having a second 105 hole which intersects an end portion of the cross-hole and terminates at one end in the member opening, a pin disposed in the cross hole with its ends terminating therein, and a locking pin disposed in the second hole 110 without an end of the cross pin and having its ends terminating in the hole.

In testimony whereof I have hereunto subscribed my name to this specification.

CHARLES W. RIBBLE.
